2,061,615

MANUFACTURE OF ALIPHATIC ACIDS,
ANHYDRIDES, AND KETONES

Henry Dreyfus, London, England,

No Drawing. Application January 25, 1933, Serial
No. 653,475. In Great Britain February 9,
1932

13 Claims. (Cl. 260—118)

This invention relates to the manufacture of oxygen-containing aliphatic compounds such as ketones, acids and anhydrides by thermal decomposition of metal salts of aliphatic acids, particularly of lower fatty acids, and more especially to the production of acetic acid, acetic anhydride, acetone or mixtures of such compounds by the thermal decomposition of metal acetates.

Metal acetates yield on thermal decomposition acetic acid, acetone or both acetic acid and acetone according to the particular metal acetate employed. Thus, acetates of the highly basic alkali and earth alkali metals (e. g. sodium, potassium, barium and calcium) and of lead yield acetone without substantial formation of acetic acid, while acetates of such metals as aluminium, manganese, and zinc yield mixtures of acetic acid and acetone, and acetates of such metals as silver, mercury, copper, chromium, and nickel yield acetic acid with little or no acetone.

Further, I have described, in my U. S. application S. No. 609,252 filed 4th May, 1932, how acetic anhydride can readily be produced by thermally decomposing the acetates of metals of low basicity, in presence or absence of normal salts of strong mineral acids, particularly when the acetates are employed in anhydrous or substantially anhydrous condition. As examples of metals of low basicity may be mentioned copper, chromium, tin, nickel. Again, in my U. S. application S. No. 609,251 filed 4th May, 1932, I have described how acetic anhydride can be produced by similarly treating acetates of highly or relatively highly basic metals in admixture with normal salts of strong mineral acids. Moreover, in my U. S. application S. No. 631,101 filed 30th August, 1932, now Patent No. 2,040,926 dated May 19, 1936 I have described how dilute acetic acid may be concentrated to any desired degree by forming therefrom an acetate of a heavy metal and subjecting the acetate, without completely dehydrating it, to thermal decomposition, whether or not in presence of a normal salt of a strong mineral acid.

It has, however, been found that when metal acetates are subjected to thermal decomposition as in the processes above referred to, certain difficulties are liable to arise in practice. In particular, especially with heavy metal acetates, sublimation of the acetate or of partially decomposed acetate is liable to occur, resulting in loss of the products of decomposition, acetic acid, acetone, acetic anhydride, and often to blocking of the apparatus with the sublimate. This difficulty is especially in evidence when local over-heating

occurs or when the decomposition is performed in a stream of gas or vapour. Moreover, it has been found difficult to obtain uniform heating of the acetates, and that unless uniform heating is attained local over-heating and consequently destructive decomposition of the reaction products is very liable to occur.

I have now found that such difficulties can readily be avoided and very satisfactory decomposition to oxygen-containing aliphatic compounds achieved if the acetates are subjected to the decomposition in admixture with or suspension in high boiling diluents. As instances of such diluents may be mentioned high boiling hydrocarbons and high boiling ethers, e. g. dibenzyl ether, phenyl benzyl ether, diphenyl ether, naphthyl aryl ethers. In general inert liquids having boiling points higher than 250°, and especially higher than 300° C., are very useful for the purposes of the invention.

The invention may be applied to the production of acetic acid, acetic anhydride, acetone or mixtures of such bodies according to the particular acetate and conditions employed. Thus, for instance, acetates of metals of low basicity may be decomposed to yield acetic anhydride or mixtures of acetic anhydride and acetic acid, the acetates being employed in simple admixture with or suspension in the diluents, salts of strong acids, e. g. sulphates, chlorides and the like also being present if desired. Non-basic acetates of copper, nickel and chromium are particularly useful for this purpose. Acetates of metals of high or relatively high basicity in admixture with normal salts of strong mineral acids and in admixture with or suspension in the diluents of the invention may also be thermally decomposed to yield acetic anhydride or mixtures of acetic anhydride and acetic acid. In order to obtain the highest possible yields of anhydride, the acetates should be employed in anhydrous or substantially anhydrous condition, i. e. free or substantially free from water of crystallization, and when they are mixed with normal salts of strong mineral acids, such salts should also be employed in the anhydrous or substantially anhydrous condition.

The invention is not, however, limited to the employment of anhydrous or substantially anhydrous acetates, as I may effect the decomposition in presence of sufficient water to produce acetic acid without any anhydride; thus I may employ heavy metal acetates which have not been completely dehydrated. Further, in cases where acetone or mixtures of acetone and acetic acid are to be produced, acetates of suitable metals may be

thermally decomposed in admixture with or suspension in high boiling diluents according to the invention; for instance acetates of aluminium, manganese or zinc may be decomposed to yield mixtures of acetic acid and acetone, while acetates of the alkali or earth alkali metals may be decomposed to yield acetone.

The thermal decomposition of the acetates according to the invention may be effected in any convenient way. For instance, the acetates in admixture with the diluents, and also, if desired, in admixture with normal salts of strong mineral acids, may be simply heated. Preferably, however, they are heated in a current or stream of an indifferent gas, e. g. air, carbon dioxide, nitrogen or the like, or of an indifferent vapor, e. g. benzol or petroleum ether. The heating may be performed at any temperature sufficient to decompose the acetate, temperatures of between about 200° C. and 450° C. being usually suitable for this purpose. Excessive temperatures liable to cause destruction of the anhydride, acid or acetone should, of course, be avoided. The decomposition may be effected at ordinary atmospheric pressure or under pressures greater or less than atmospheric.

Preferably such diluents are employed as have boiling points sufficiently high to avoid substantial evaporation during the decomposition. Loss of diluent by distillation or evaporation may, however, be prevented or minimized by heating the acetate diluent mixture under reflux.

The invention is not restricted simply to the thermal decomposition, but embraces all processes and manufactures comprising the thermal decomposition of acetates according to the invention. For instance, it may be applied to the concentration of aqueous acetic acid, or to the recovery of concentrated acetic acid and/or anhydride from waste acetylation liquors, as described in my U. S. applications S. Nos. 609,251, 609,252 and 631,101, or to the manufacture of acetone from acetates of more basic metals such as calcium acetate.

The preparation of more concentrated acetic acid and/or acetic anhydride from dilute industrial acetic acid forms a very important feature of the invention. As above indicated, this may be effected by treatment of the dilute or waste acids to form suitable acetates, which acetates, whether or not in admixture with normal salts of strong mineral acids, after removal of water to the extent desired, are subjected to thermal decomposition according to the invention. Preferably the dilute or waste acids are treated with oxides, carbonates or other appropriate compounds of metals of low basicity to yield the acetates, oxides or other compounds of copper, nickel or chromium being particularly useful for this purpose. The formation of the acetates and the removal therefrom of excess water can be effected in any convenient way, as for instance by the methods referred to in my U. S. application S. No. 631,101. Thus the oxides or other substances may be added to the acid liquor, preferably at an elevated temperature and in stages. The salt formed may be partially or completely separated from the solution by evaporation of the water; preferably however, the acetate is allowed to crystallize out on cooling, if necessary after partial evaporation of the water; frequently the separation may also be assisted by the addition of another and more soluble acetate, or of an organic liquid in which the salt is insoluble.

The acetates may be removed from the solu-

tion by filtration, centrifuging, decantation, or in any other way, and further adherent or combined water removed if desired, by heating; such water may, however, be removed in other ways. The acetates may be mixed with or suspended in the high boiling inert diluents at any stage in the process, before or after the removal of adherent or combined water. For instance, when acetates containing adherent or combined water, part or all of which is to be removed before the acetate is decomposed, are separated from the liquors, such acetates may advantageously be heated in admixture with or suspension in diluents according to the invention to remove water, before they are subjected to thermal decomposition.

While the invention has been described more particularly with reference to the thermal decomposition of acetates, it is in nowise limited thereto, but includes the thermal decomposition of salts of higher aliphatic acids and especially of other lower fatty acids in presence of high boiling inert diluents. For instance, I may employ the corresponding propionates or butyrates in place of the acetates to obtain the corresponding anhydrides, acids or ketones. Moreover, the invention may be applied inter alia to the recovery of such anhydrides, acids or ketones from dilute or waste higher aliphatic acids.

The invention is illustrated by the following example, but it is of course in no way limited thereby.

Example

To 300 gallons of acetic acid of approximately 25% concentration, recovered from a cellulose acetylation, and heated to 80° C. is gradually added 350 lbs. of cupric oxide. The solution is allowed to cool, whereupon copper acetate mainly in the form of the penta-hydrate is separated out. This salt is then filtered off from the mother liquor, and added to approximately its own weight of a petroleum fraction of boiling point between 290° and 330° C. The mixture is heated to 90° C. to remove most of the water, and the temperature is then raised to 280° C. Acetic acid distils over, and may be recovered in a very concentrated form.

What I claim and desire to secure by Letters Patent is:—

1. The manufacture of oxygenated organic compounds which comprises thermally decomposing a metal salt of an aliphatic acid in the presence of an inert high boiling diluent that is liquid at the temperature of treatment.

2. The manufacture of oxygenated organic compounds which comprises thermally decomposing a metal salt of a lower fatty acid in the presence of an inert high boiling diluent that is liquid at the temperature of treatment.

3. The manufacture of oxygenated organic compounds which comprises thermally decomposing an acetate of a metal in the presence of an inert high boiling diluent that is liquid at the temperature of treatment.

4. The manufacture of oxygenated organic compounds which comprises thermally decomposing a metal salt of a lower fatty acid in the presence of a high boiling hydrocarbon that is liquid at the temperature of treatment.

5. The manufacture of oxygenated organic compounds which comprises thermally decomposing a metal salt of a lower fatty acid in the presence of a high boiling ether that is liquid at the temperature of treatment.

6. The manufacture of oxygenated organic

compounds which comprises thermally decomposing an acetate of a metal in the presence of a high boiling hydrocarbon that is liquid at the temperature of treatment.

5 7. The manufacture of oxygenated organic compounds which comprises thermally decomposing an acetate of a metal in the presence of a high boiling ether that is liquid at the temperature of treatment.

10 8. The manufacture of oxygenated organic compounds which comprises heating to a temperature at which it thermally decomposes a metal salt of a lower fatty acid in admixture with a normal salt of a strong mineral acid in

15 the presence of an inert high boiling diluent that is liquid at the temperature of treatment.

9. The manufacture of oxygenated organic compounds which comprises heating to a temperature at which it thermally decomposes an acetate of a metal in admixture with a normal salt of a strong mineral acid in the presence of an inert high boiling diluent that is liquid at the temperature of treatment.

20 10. The manufacture of oxygenated organic compounds which comprises heating a metal salt of a lower fatty acid to a temperature between 200° and 450° C. in the presence of an inert high

boiling diluent that is liquid at such temperatures.

11. The manufacture of oxygenated organic compounds which comprises heating an acetate of a metal to a temperature between 200° and 450° C. in the presence of an inert high boiling diluent, that is liquid at such temperatures.

12. The manufacture of oxygenated organic compounds which comprises forming a metal salt of a lower fatty acid from an aqueous solution containing the said acid, separating the salt from the solution, removing at least part of its water content and subjecting the salt to thermal decomposition at a temperature between 200° and 450° C. in presence of an inert high boiling diluent that is liquid at such temperatures.

13. The manufacture of oxygenated organic compounds which comprises forming an acetate of a metal from an aqueous solution containing acetic acid, separating the acetate from the solution, removing at least part of its water content and subjecting the acetate to thermal decomposition at a temperature between 200° and 450° C. in presence of an inert high boiling diluent that is liquid at such temperatures.
